PROCESS FOR THE PRODUCTION OF
LUBRICATING OIL

David R. Merrill, Long Beach, Calif., assignor to
Union Oil Company of California, Los Angeles,
Calif., a corporation of California

Application October 24, 1932, Serial No. 639,342

7 Claims. (Cl. 196—13)

This invention relates to a process for the production of lubricating oil. More specifically it relates to a process for the production of lubricating oil from petroleum by the use of solvents.

5 One of the distinctive characteristics of a lubricating oil is its viscosity. Its usefulness as a lubricant depends, at least in part upon its viscosity. For many purposes lubricants are desired whose viscosity will vary as little as possible with 10 variations in temperature, i. e., have low temperature viscosity susceptibilities. Those fractions which exhibit a low temperature viscosity susceptibility are oftentimes referred to as the paraffinic oils whereas the fractions which exhibit a high 15 temperature viscosity susceptibility are referred to as the non-paraffinic oils.

The heavy oil fractions of many crude oils, from 20 which lubricating oils are produced consist of a mixture of hydrocarbons some of which exhibit a low temperature viscosity susceptibility, some of which exhibit an intermediate temperature viscosity susceptibility, and some of which exhibit a high temperature viscosity susceptibility. In order to produce superior lubricating oil from 25 hydrocarbon mixtures, as described above, those oils present having a high viscosity temperature susceptibility and those having an intermediate temperature viscosity susceptibility are separated from the oils present which exhibit a low temperature viscosity susceptibility. Solvent extraction 30 is one of the methods employed to separate the undesirable oil from the desirable oil. Solvents, such as aniline, furfural, nitrobenzene, selenium oxychloride, sulphur dioxide or B B' dichlorethyl ether are capable, under the proper 35 conditions of temperature and pressure, of dissolving the fractions present which are non-paraffinic in character.

The foregoing solvents under proper conditions 40 of temperature and pressure are capable of dissolving the oils present in the hydrocarbon mixture which exhibit intermediate and low temperature viscosity susceptibilities. These oils dissolved in the solvent may then be separated from 45 each other by cooling in which case the oils exhibiting the intermediate temperature viscosity susceptibility are forced out of solution.

These solvents form relatively heavy solutions 50 with the non-paraffinic oil fractions and can be separated from the insoluble paraffinic oil fractions by settling. The separated paraffinic oil fractions or raffinates and non-paraffinic oil fractions or extracts dissolved in solvent are then 55 distilled to separate the solvent from the oil. The paraffinic fractions may then be given such

further treatment as necessary to remove any remaining impurities. The non-paraffinic oil fractions being relatively valueless are utilized as fuel or as cracking stock in conversion processes.

The separation of hydrocarbon mixtures into 5 paraffinic and non-paraffinic fractions by the use of solvents is not restricted to batch operation but may be carried out in a continuous manner. Where continuous extraction is employed it is customary to flow the solvent countercurrently 10 to the oil to be extracted. Hence the oil being purified is progressively being contacted with solvent which is less contaminated with non-paraffinic fractions. The oil entering the extraction system is contacted with solvent containing 15 a relatively high concentration of non-paraffinic fractions whereas the purified oil is finally contacted with pure solvent. In this manner the maximum degree of refinement is usually obtained because at the final stage of the extraction 20 relatively pure oil is contacted with fresh solvent which has a high selective solvent power to separate the paraffinic and non-paraffinic fractions because it is not contaminated with non-paraffinic oil. When continuous countercurrent extraction is employed the extraction step may be carried out in one stage wherein the solvent and 25 oil flow countercurrently or it may be carried out in a plurality of stages wherein the extracts obtained from the later stages of the process are 30 returned to the earlier stages of the process and employed therein as the extracting medium. Thus in the first extraction stage the oil to be extracted is contacted with solvent containing dissolved fractions from a later stage. The insoluble oil portion in the first stage passes to the 35 second stage where it is contacted with solvent containing less of the extracted fractions. The insoluble oil from the second stage passes successively in the same manner as described above, 40 to the remaining extraction stages until it reaches the final stage wherein it is extracted with pure solvent. In processes of this character the same 45 temperature is employed throughout the system and as final products there are obtained a fraction consisting largely of the non-paraffinic fractions and a fraction which is in the main composed of the paraffinic fractions.

I have found that it is highly desirable to extract oil in stages countercurrently with a solvent. Furthermore, I have found that a more economical use of solvent can be obtained where the solvent and dissolved fractions from a later stage of the extraction is partially deprived of its 50 dissolved fractions before passing it to an earlier 55

stage to be employed therein as the extracting medium.

It is, therefore, an object of my invention to extract oil countercurrently in stages with a solvent and to deprive the solvent passing from a later extraction stage of a portion of its dissolved fractions before employing it as a solvent medium in an earlier stage.

It is another object of my invention to extract oil countercurrently in stages with a solvent, to deprive the solvent passing from a later extraction stage of a portion of its dissolved fractions and then to pass this partially purified solvent to an earlier extraction stage operating at the same or at a different temperature than said later stage.

Fig. 1 is a schematic arrangement of apparatus which may be employed in carrying out my process.

Fig. 2 is a schematic arrangement of another form of apparatus in which my process may be carried out.

Fig. 3 is a cross section of an orifice mixer which I employ to produce an intimate mixture between two immiscible liquids. The fluids in pipe A pass successively through the diaphragms B, B', and B'' which are provided with openings C, C', and C''. After leaving the constricted openings C, C', and C'', the fluid passes into chambers D, D', and D''. The passage of the immiscible liquids through the diaphragm into the enlarged chambers D, D', and D'' produces sufficient turbulence to insure intimate contact of these fluids.

Referring more particularly to Fig. 1, the oil to be extracted enters the extraction apparatus through line 1 from a source not shown and enters pump 2 which forces it through line 3, and valve 4 to cooler 5. The cooled oil emerges from cooler 5 into line 6 where it meets a stream of solvent coming from heat exchanger 95 through line 117. The mixture of oil and solvent passes through orifice mixer 7 where they are intimately mixed. The mixture in orifice mixer 7 passes through line 8 into settling tower 9 where the solvent containing dissolved fractions settles to the bottom owing to its relatively high specific gravity, and the insoluble paraffinic oil fractions rise to the top owing to their relatively low specific gravity and are removed from the settling tower 9 through line 10.

The solvent containing the dissolved non-paraffinic fractions in the lower zone of settling tower 9 is removed through line 96, valve 97 and sent by pump 98 through line 114, valve 115 and line 116 to distillation means where the solvent is separated from the extract. As a modification, the extract from line 114 may be passed to heat interchanger 93 where it is cooled to a point sufficiently low to cause a separation of a portion of the most paraffinic oil fractions present, from the non-paraffinic fractions which are dissolved in the solvent. The cooled mass in interchanger 93 passes through line 100 to separator 101 where the insoluble oil fractions rise to the top and are removed through line 102. The solvent and dissolved fractions in separator 101 are removed through line 103, valve 104, line 105 and valve 106 into line 116 from which it passes to distillation means, not shown, to separate the solvent from the extract; or instead of passing to line 116, it may pass to cooler 107 where a further cooling of the solvent and dissolved fractions takes place and a further separation of oil fractions at this reduced temperature takes

place. The mixture in cooler 107 then passes through line 108 to separator 109 where the insoluble fractions rise to the top and are removed through line 110. The solvent containing the dissolved fractions may then be removed through line 111 and valve 113 into line 116 where it passes to distillation means for separating the solvent and dissolved fractions; or it may pass through valve 112, line 90, valve 91 and line 92 to heat exchanger 93 where its temperature is raised by indirect thermal contact with the relatively warm fluid in line 114. After passing from interchanger 93, the solvent and remaining dissolved fractions pass to heater 95 where their temperature is raised preferably to a point equal to that of the oil being discharged from heater 5.

The insoluble oil fraction in the uppermost zone of settling tower 9, is removed through line 10 to orifice mixer 11 where it is mixed with solvent coming from heater 72 through line 118. The mixed solvent and oil pass into settling chamber 13 where the light insoluble fraction rises to the uppermost zone and is removed through line 14. The solvent and dissolved fractions in settling chamber 13 gravitate to the lower zone of chamber 13 and are removed through line 13, valve 14, pump 75 and line 76 to heat exchanger 70 where the temperature of the solvent and dissolved fractions is lowered sufficiently to cause a portion of the fractions dissolved in the solvent to be forced out of solution. The solvent containing the immiscible or undissolved fractions in exchanger 70 then passes through line 77 into separator 78 where the insoluble fractions owing to their lower specific gravity, rise to the top and are withdrawn through line 79. The solvent and remaining dissolved fractions in separator 78 settle out and are withdrawn through line 80, valve 81 and line 82 to cooler 83 where the temperature of this solution is again lowered to cause a further separation of oil at this lowered temperature. The cooled mass in cooler 83 is withdrawn through line 84 into settling chamber 85 where the insoluble oil rises to the top and is withdrawn through line 86. The solvent and remaining dissolved fractions in settling chamber 85 are withdrawn through line 87, valve 88, line 90, valve 91, line 92, heat exchanger 93, line 94, heater 95 and line 117 into line 6 where they are employed as solvent for the oil being discharged from heater 5. If desired, a portion of the solvent and dissolved fractions in line 111 may be mixed with the solvent in line 90, which has been obtained as previously described from settling chamber 85 through line 87, and valve 89, by opening valve 112.

The insoluble oil fraction being removed from the upper zone of chamber 13 through line 14 passes to orifice mixer 15 where it is mixed with solvent from line 119. This mixed mass passes through line 16 to settling chamber 17 where the insoluble oil fractions rise to the top, because of their lower specific gravity, and are removed through line 18. The heavy solvent with its dissolved fractions in settling chamber 17 is removed through line 50, valve 51, pump 52 and line 53 to heat exchanger 47 where its temperature is lowered sufficiently to cause a separation of a portion of the dissolved fractions. The cooled mass in exchanger 47 passes through line 54 to settling chamber 55 where the insoluble oil fractions rise to the top and are removed through line 56. The solvent and remaining dissolved fractions in settling chamber 55 are removed through line 57, valve 58 and line 59 to

cooler 60 where the solution of solvent and oil is further cooled sufficiently to cause further separation of oil from the solvent. The cooled mass is passed from cooler 60 through line 61 to separator 62 where the insoluble oil rises to the top and is removed through line 63. The heavier solvent containing dissolved fractions gravitates to the bottom of settling chamber 62 and is removed through line 64, valve 66, line 67, valve 68 and line 69 to heat exchanger 70 where its temperature is raised by indirect heat exchange after which it passes through line 71 and heater 72 to line 118 where it is mixed with oil from line 10 as hereinbefore described. If desired, the solvent and dissolved fractions in line 64 may be mixed with a portion of the solvent and extracted fractions from chamber 85 by opening valve 88.

The oil in line 18 passes to mixer 19 where it is mixed with fresh solvent introduced through line 23, pump 24, line 25, heater 26 and line 120, passes into orifice mixer 19 along with the oil from line 18. Here the oil is thoroughly mixed with the solvent and passed into settling chamber 21. The light insoluble oil fractions rise and are removed through line 22 to storage, not shown. This material constitutes the most paraffinic fractions contained in the raw stock introduced through line 1. This fraction may now be given any further treatment, such as with acid, alkali and/or clay for the production of a highly paraffinic lubricating oil. The solvent and dissolved fractions in settling chamber 21 gravitate to the bottom and are removed through line 27, valve 28, pump 29 and line 30 to cooler 31 where they are cooled sufficiently to cause separation of a part of the oil from solution. The cooled mass in cooler 31 is withdrawn through line 32 to settling chamber 33 where the insoluble oil rises to the top and is removed through line 34. The solvent containing dissolved fractions gravitates to the bottom of chamber 33 and is removed through line 35, valve 36 and line 37 to cooler 38 where it is again cooled sufficiently to cause a further separation of oil from the solvent and dissolved fractions. The mass in cooler 38 is withdrawn through line 39 to separator 40 where the insoluble oil, being lighter than the solvent, rises to the top and is removed through line 41. The solvent and dissolved fractions gravitate to the bottom of separator 40 and are removed through line 42, valve 43, line 44, valve 45, line 46, interchanger 47, line 48, heater 49 and line 119 into mixer 15 where they are mixed with oil coming from line 14. If desired, the solvent and dissolved fractions withdrawn from settling chamber 40 by way of line 42, valve 43 and line 44 may be mixed with solvent containing dissolved fractions removed from the bottom of settling chamber 62 by opening valve 65.

In Fig. 1 the flow of the solvent is countercurrent to the oil to be extracted. After each extraction step, the solvent is partially deprived of its dissolved fractions through cooling and settling. The partially purified solvent is then heated and employed as a solvent medium in an earlier extraction stage.

Referring more particularly to Fig. 2, the stock to be treated enters line 201 from a source not shown and passes through pump 202, line 203, valve 204, line 205 to cooler 206 where the temperature of the oil is decreased. From cooler 206 the oil passes to the lower zone of column 208. Here it is countercurrently extracted with solvent introduced into the upper zone of column

208 through line 293 and at a temperature substantially equal to that of the oil introduced into the lower zone of column 208. The solvent introduced at the top of the column 208 being heavier than the oil passing downward through the rising column of oil introduced into the lower zone of column 208 and extracts therefrom certain of the non-paraffinic fractions. The insoluble oil from which there has been extracted the non-paraffinic fractions is removed from column 208 through line 209. The solvent and dissolved fractions are removed from column 208 through line 294, valve 295, pump 296, and line 297. At this point in the process, valve 298 may be opened and the solvent and extracted fractions or a portion thereof may be sent through line 306 to distillation means in order to separate the solvent from the extract, or the solvent and dissolved fractions may be passed through heat exchanger 290 which cools the solution and causes oil fractions to separate from the solvent solution. The cooled mass in exchanger 290 passes through line 300 to separator 301 where the light insoluble fractions rise to the top and are withdrawn through line 315. The heavy solvent and remaining dissolved fractions gravitate to the bottom of separator 301. The fractions or a portion thereof, are removed through line 302, valve 303, line 304 and valve 305 to distillation means to separate the oil and solvent; or valve 305 may be closed, in which case, the solvent and dissolved fractions pass through cooler 307 to further separate oils dissolved therein. The cooled mass in separator 307 is removed through line 308 into separator 309 where the insoluble light oil fractions rise to the top and are removed through line 310. The solvent and remaining fractions are then removed from settling chamber 309 through line 311, valve 313 and line 306 to distillation means, to separate the solvent from the extract.

The oil fraction in line 209 passes to the lower zone of extraction column 210 where it is countercurrently extracted with solvent introduced into the upper zone of column 210 by means of line 268.

The heavy solvent introduced into the upper zone of column 210 moves downward through the ascending column of relatively light oil and extracts therefrom certain non-paraffinic fractions. The oil from which the non-paraffinic oil has been extracted is removed from column 210 through line 211. The solvent and extracted fractions in column 210 are removed through line 269, valve 270, line 271, pump 272 and line 273 to heat exchanger 265, which cools them and causes a portion of the oil to be forced out of solution. The cooled mass in exchanger 265 is removed through line 274 into settling chamber 275 where the insoluble light oil rises to the top and is removed through line 276. The solvent and dissolved fractions are removed through line 277, valve 278 and line 279 into cooler 280 where a further separation of oil takes place. The cooled mass in cooler 280 passes through line 281 into settling chamber 282 where the oil rises to the top and is removed through line 283. The heavy solvent and extracted fractions are removed from the bottom of chamber 282 through line 284, valve 286, line 287, valve 288, line 289 to heat exchanger 290 where they are heated and then passes through line 291 to heater 292 where their temperature is again increased after which they pass by means of line 293 into extraction column 208. If desired, the solvent and dissolved frac-

the apparatus is to draw off and dissolved fractions may be removed from the bottom of column 282 through line 284, valve 286 into line 287 and there blended with a portion of the solvent withdrawn from settling chamber 309 through line 311 and valve 312.

The oil in line 211 passes to the bottom of extraction column 212 where it is countercurrently extracted with solvent introduced through line 243 into the upper zone of column 212. The heavy solvent introduced through line 243 into the upper zone of column 212 passes downward through the relatively lighter column of ascending oil and extracts certain non-paraffinic fractions therefrom. The rising column of oil, from which certain non-paraffinic fractions have been extracted, is removed through line 213.

The heavy solvent and dissolved fractions in column 212 gravitate to the bottom and are removed through line 244, valve 245, line 246, pump 20 247 and line 248 to heat exchanger 240 where they are cooled sufficiently to cause separation of a portion of the extract from solution. The cooled mass passes by way of line 249 into separator 250 where the light insoluble oil rises to the top and is removed through line 251. The solvent and dissolved fractions settle to the bottom of separator 250 and are removed through line 252, valve 253 and line 254 to cooler 255 where they are further cooled and further oil fractions separated. The cooled mass in cooler 255 is then passed through line 256 into separator 257 where the insoluble oil fractions rise to the top and are removed through line 258. The solvent and remaining dissolved fractions settle out and are removed from chamber 257 through line 259, valve 261, line 262, valve 263 and line 264 to heat exchanger 265 where their temperature is raised, after which they pass through line 266 to heater 267 where a further increase in temperature takes place. The heated solvent is then discharged through line 243 into column 212. If desired, valve 285 may be opened and a portion of the solvent from chamber 282 mixed with the solvent in line 262 coming from the bottom of chamber 257.

The oil in line 213 passes to the lower zone of column 214 where it is countercurrently extracted with fresh solvent introduced through line 314, pump 216, line 217, heater 218 and line 316 into the upper zone of column 214. The descending column of heavy solvent extracts a portion of the non-paraffinic fractions from the ascending relatively light column of oil. The oil from which the non-paraffinic fractions have been removed passes from the extraction apparatus through line 215 to storage, not shown, and may be given any further treatment with acid, alkali and/or clay to produce a finished oil.

The solvent and dissolved fractions in column 214 settle out and are removed through line 219, valve 220, line 221, pump 222 and line 223 to cooler 224 where their temperature is lowered sufficiently to cause a portion of the dissolved fractions to settle out. The cooled mass from cooler 224 is withdrawn through line 225 to separator 226 where the insoluble oil rises to the top and is removed through line 227. The solvent containing dissolved fractions settles out and is withdrawn through line 28, valve 229 and line 230 into cooler 231 where its temperature is again lowered and further separation of dissolved fractions takes place. The cooled mass in cooler 231 is withdrawn through line 232 into separator 233 where the insoluble oil fractions rise and are

withdrawn from the separator through line 234.

The solvent and dissolved fractions in separator 233 settle out and are removed through line 235, valve 236, line 237, valve 238 and line 239 to heat exchanger 240 where their temperature is raised after which they pass by means of line 241 into heater 242 where a further increase in temperature takes place. They then pass through line 243 into extraction column 212. If desired, a portion of the solvent settled out in chamber 257 may be mixed with the solvent in line 237 coming from chamber 233 by opening valve 260.

The oil is thus subjected to multiple countercurrent extraction with cooling of the extract phases from the later stages for rejection of a low grade raffinate before use of the extract phase as solvent in the earlier stages. It will be noted that I may employ any desired number of stages with the oil finally being extracted with fresh solvent. The raffinate phases separating out on cooling the extracts from the various stages may be combined in any desired way in accordance with their respective qualities, either before or after exhaustion of their solvent content. From the first stage, in which the fresh stock is brought into contact with the most contaminated solvent, the extract phase may be drawn off for distillation either before or after cooling as indicated. In general, however, it appears desirable to cool and obtain a separation of a raffinate phase before sending the solution to the still as by this means a final extract of highest aromatic character will be obtained. Although in Fig. 1, a simple mixing of the solvent with the oil phase followed by phase separation is shown, it is possible and probably desirable, at least in the last stage, to substitute for this a countercurrent extracting column as shown in Fig. 2.

While it will often be found convenient to operate each of the stages of extraction at the same temperature, it is of course possible to operate each successive stage at a different temperature. Thus, for example, the extraction may be carried out with a gradually rising temperature in each successive stage in order to increase the solvent power of the solvent in the later stages and thereby reduce the quantity of solvent required for attaining a given degree of refinement. I do not limit my process, however, to the use of the same temperatures in each successive stage nor to the use of higher temperatures in each successive stage, as in some cases it may be found desirable to operate at lower temperatures in each successive stage. Furthermore, it will be understood that my process is independent of the number of stages employed and may be used in any extraction system wherein a plurality of extraction stages are employed. The optimum conditions of temperature for each successive stage

will vary to some extent according to the character of the oil treated, the character of the solvent, the amount of solvent employed, and the degree of refinement required in the final raffinate. In general it appears that the maximum economy of solvent for any particular required degree of refinement will be obtained by operating the last stage at as high a temperature as is feasible, or in other words, with the minimum practicable margin between the operating temperature and the temperature of complete miscibility under the particular conditions. In operating the second stage of a two stage system at the maximum feasible temperature, the quantity of solvent to be employed will be the minimum

required to give a raffinate of the desired degree of paraffinicity. After the relative proportions of solvent and feed stock are thus established, the temperature of the first stage will then be chosen so as to obtain the desired relationships of yield and quality between the extract and the intermediate raffinate. Thus if the first stage is operated at as low a temperature as is economically feasible, an extract phase will be obtained of maximum aromatic character and the intermediate raffinate phase will be obtained in maximum yield. If at this low temperature an excessive quantity of extract of insufficiently aromatic character is produced, due to the use of an excessive amount of solvent in the first stage, the excess extract phase not required for the first stage may be bled off either before or after cooling and passed to a still for recovery of solvent and an intermediate grade of oil. If, on the other hand, the first stage is operated at a somewhat higher temperature but still substantially below the temperature employed for the second stage, the yield of extract will be increased but it will not be so predominantly of aromatic character because of inclusion in the extract of compounds of intermediate paraffinicity which under the previous conditions were obtained in the intermediate raffinate. The yield of intermediate raffinate will be correspondingly reduced, but its quality will be improved due to the more complete elimination of compounds of intermediate grade in the extract. Additional solvent may even be added between the two stages to improve the quality of the intermediate raffinate, although ordinarily this is not as economical as adding all of the solvent in the last stage. For any particular stock and solvent, the ratio of solvent to stock and the temperatures of the two stages may be chosen in accordance with the principles just discussed to separate the oil into the three fractions of most suitable quality for any particular set of marketing conditions.

As extracting medium, I may employ such solvents as aniline, nitrobenzene, B B' dichlorethyl ether, methyl cellosolve, sulphur dioxide or mixtures thereof. Furthermore, the process may be applied to distilled or residual oils or to oils which have been diluted with hydrocarbon diluents varying from heavy diluents such as kerosene to light diluents of the normally gaseous type, such as propane. The primary purpose of mixing the oil with diluents is to reduce its viscosity so as to facilitate mixing and phase separation. It is therefore, evident that the use of diluents is of value primarily with the more viscous oils and in operation at fairly low temperatures such that the viscosity of the undiluted oil renders mixing and phase separation difficult. Since it is ordinarily only the raffinate phase which exhibits excessive viscosity, the diluents employed should preferably be of the paraffinic type so they will tend to remain in the raffinate phase and from the standpoint of economy the quantity of diluent should be held to the minimum required to give the desired reduction in viscosity. It will ordinarily be found that the addition of one part naphtha to two parts of oil will give an adequate degree of fluidity.

As a specific example a dewaxed Santa Fe Springs lubricating oil stock was countercurrently extracted in a two stage extraction process with 200 volume per cent of B B' dichlorethyl ether. The temperature in the first extraction stage was 44° F. and the temperature of the second stage was 120° F.

The products recovered from the two stage extraction consisted of an extract, an intermediate raffinate and a final raffinate. These products were then distilled to remove the solvent from the oil. As the final raffinate fraction withdrawn from the extraction process at 120° F. contains an appreciable quantity of solvent and extract fractions in solution, it may be found desirable to cool this fraction to a temperature of approximately 40° F., pass the cooled mass to settling means and allow the separated solvent and dissolved fractions to settle from the raffinate oil. The raffinate oil from the cooler may then be sent to distillation means to separate the remaining solvent present and the solvent and extracted fractions may be returned to the first extraction stage where it may be employed therein as extraction medium for the incoming oil.

The following table shows the characteristics of the raw stock, the extract, the intermediate raffinate and the final raffinate recovered from the two stage extraction process described above:

	% Yield	Gr. ° A. P. I. at 60° F.	Viscosity S. S. U. at 20° F.	Viscosity index Dean and Davis	Viscosity gravity constant
Stock.....	100	19.9	104	51	.867
Extract.....	33	10.2	202	-8	.939
Intermediate raffinate.....	36	24.1	90	76	.835
Final raffinate.....	26	26.0	94	88	.821

As will be noted the viscosity index of the final raffinate is 88. With another stage of extraction this value can be somewhat increased.

The viscosity index referred to in the table is defined by Dean and Davis in Chemical and Metallurgical Engineering, vol. 36, 1929, page 618. The viscosity index of a lubricating oil is an indication of its composition or type, i. e., whether it is a paraffin or naphthene base oil. Paraffin base oils are arbitrarily assigned a viscosity index of 100, and certain naphthene base oils from the Gulf Coast are assigned a viscosity index of 0 and mixed base oils lie between these extremes.

The gravity-viscosity constant referred to in the table is defined by Hill and Coats in the Journal of Industrial and Engineering Chemistry, vol. 20, page 641 (1928). This constant represents the paraffinicity or naphthenicity of a given oil. A high value indicates a high degree of naphthenicity while low values indicate relatively greater paraffinicity. Lubricating oils from natural crudes range from .903 (for an extreme Gulf Coast type) to .807 for an extreme Pennsylvania type, or even beyond.

The foregoing example is merely illustrative of one method of carrying out my invention and is not to be construed as limiting the invention which I claim.

I claim:

1. A process for the separation of paraffinic from the non-paraffinic fractions of a hydrocarbon oil mixture which comprises extracting a raffinate from an earlier extraction stage with a solvent into a second raffinate and fractions dissolved in said solvent, cooling said solvent containing dissolved fractions to separate an insoluble fraction therefrom, removing said solvent and remaining dissolved fractions from said insoluble fraction, subsequently passing the solvent and remaining dissolved fractions to said earlier extraction stage and extracting a hydrocarbon oil

mixture passing to said earlier extraction stage into a plurality of fractions.

2. A process for the separation of paraffinic from the non-paraffinic fractions of a hydrocarbon oil mixture which comprises extracting a raffinate from an earlier extraction stage with a solvent into a second raffinate and fractions dissolved in said solvent, cooling said solvent containing dissolved fractions to separate an insoluble fraction therefrom, removing said solvent and remaining dissolved fractions from said insoluble fraction, subsequently passing said solvent and remaining dissolved fractions to said earlier extraction stage and extracting a hydrocarbon oil mixture passing to said earlier extraction stage into a raffinate and fractions dissolved in the solvent containing the remaining dissolved fractions.

3. A process for the separation of paraffinic from the non-paraffinic fractions of a hydrocarbon oil mixture which comprises extracting a raffinate passing from an earlier extraction stage into a plurality of fractions with a solvent, one of said fractions containing solvent and dissolved fractions, cooling said solvent containing dissolved fractions to separate an insoluble fraction therefrom, separating said solvent and remaining dissolved fractions from said insoluble fraction, subsequently passing said solvent containing the remaining dissolved fractions to said earlier extraction stage, and extracting oil passing to said earlier extraction stage into fractions dissolved in said solvent containing the remaining dissolved fractions and said raffinate passing from said earlier stage of extraction.

4. A process for the separation of paraffinic and non-paraffinic fractions from a hydrocarbon oil mixture containing the same which comprises extracting said oil with a solvent in a primary stage into a raffinate and fractions dissolved in said solvent, passing said raffinate to a secondary extraction stage and extracting said raffinate with a solvent into a second raffinate and fractions dissolved in said solvent, cooling said solvent and dissolved fractions from said secondary extraction stage to separate an insoluble fraction therefrom, separating said solvent from said secondary extraction stage containing the remaining dissolved fractions from said insoluble fraction and passing said solvent from said secondary extraction stage containing remaining dissolved

fractions to said primary extraction stage to extract said oil passing to said primary extraction stage.

5. A process for the separation of paraffinic from non-paraffinic fractions of a hydrocarbon oil mixture containing the same which comprises passing said oil into a primary extraction stage, extracting said oil with a solvent in said primary extraction stage into a raffinate and an extract dissolved in said solvent, passing said raffinate into a secondary extraction stage and extracting said raffinate with a solvent into a second raffinate and a mixture of extract and intermediate raffinate dissolved in said solvent, cooling said latter mixture to separate said intermediate raffinate therefrom, separating said intermediate raffinate from said solvent containing the remaining dissolved extract and passing said solvent containing said remaining dissolved extract to said primary extraction stage to extract said oil passing into said primary extraction stage.

6. A process for treating oil to produce lubricating oil which comprises extracting a raffinate produced by extraction of oil with a solvent with fresh solvent to produce a raffinate and a mixture of extract and solvent containing an intermediate raffinate, cooling said mixture to separate said intermediate raffinate from said solvent and extract, removing said intermediate raffinate from said solvent and extract and treating fresh oil with said extract and solvent free from said intermediate raffinate to produce said first mentioned raffinate.

7. A process for the production of lubricating oil from a hydrocarbon oil mixture which comprises separating a second raffinate and B B' dichlorethyl ether containing dissolved fractions in a later extraction stage, cooling said B B' dichlorethyl ether containing dissolved fractions to separate an insoluble fraction therefrom, removing said insoluble fraction from the B B' dichlorethyl ether and remaining dissolved fractions, passing said B B' dichlorethyl ether containing the remaining dissolved fractions to an earlier extraction stage and extracting said hydrocarbon oil mixture passing to said earlier extraction stage into a raffinate and fractions dissolved in said B B' dichlorethyl ether.
